In Great Britain June 27, 1942

12 Claims. (Cl. 250—27.5)

This invention relates to the mounting of electrodes in electric discharge tubes and more particularly to tubes of the type in which at least one electrode is mounted at each end of the envelope.

For certain purposes discharge tubes of the usual type in which all the electrodes are carried by a common pinch, or foot, are undesirable. Examples of such purposes are where discharge tubes are required to withstand high mechanical stress, or to operate under such a condition, or for short-wave work, where inter-electrode capacity must be as low as possible; for these purposes the type of tube in which an electrode is mounted at each end of the envelope is to be preferred. Where the tube has a cathode activated by the deposition thereon of an alkali metal, it is also highly desirable that the tube be of the double-ended type in order that the cathode may be maintained at low temperature whilst other parts of the tube are heated to ensure that the alkali metal is deposited only on the cathode.

Where discharge tubes are produced in quantity by mass production it has been found necessary to use such means as insulating inter-electrode spacers in order to obtain products having characteristics which vary as little as possible from one another. If such means are not employed wide variations of characteristics are difficult to avoid due to relatively small variations of spacing of the electrodes. Where the cathode is to be activated as described above such spacers are objectionable owing to the likelihood of the formation thereon of conducting films which would cause electrical leakage between the electrodes held by the spacers.

The main object of the present invention is to provide a form of construction of electric discharge tubes which ensures that all products of the same manufacturing process are as nearly identical as possible to one another in respect of their characteristics, and which avoids the use of inter-electrode spacers.

The characteristics of such tubes are to a very great extent dependent on the spacing between electrodes and the aim of the invention is to ensure that such spacing is determined accurately without the use of inter-electrode spacers. Thus any slight variations in the characteristics which may still occur between the several products made in accordance with the invention are mainly those which arise from other factors, such as the chemical nature of the cathode surface and will be relatively small.

The invention is particularly useful for so-called midget tubes.

According to the invention an electric discharge tube comprises a glass envelope having an internal ledge formed by stepping the inner diameter of the wall thereof, at least one electrode mounted at one end of said envelope, in pre-determined location therein, both by reference to said ledge and to the part of the wall adjacent thereto, and another electrode which is prevented from undergoing both axial and tilting displacement by abutment against said ledge and from undergoing lateral displacement by contact with the part of the wall adjacent to said ledge, whereby said electrodes are located in desired spatial relationship to one another.

Also in accordance with the present invention a method of constructing a discharge tube includes the formation of at least one internal ledge in a glass cup-like member by stepping the diameter of the wall thereof in such manner that said ledge faces the mouth of said member, abutting a jig holding at least one electrode against said ledge to prevent both axial and tilting displacement thereof and against the part of the wall of said cup-like member adjacent to said ledge to prevent lateral displacement, mounting the said electrode in the envelope whilst so held by the jig, removing said jig, inserting another electrode into said cup-like member and closing the mouth of the latter member in such a manner as to hold said other electrode in contact with said ledge to prevent both axial and tilting displacement thereof and with the part of the wall of said member adjacent to said ledge to prevent lateral displacement, whereby said electrodes are located in desired spatial relationship to one another.

Referring to the accompanying drawing:

Figure 1 is a vertical cross-sectional view of a cup-like member forming part of the envelope of the tube;

Figure 2 is a similar view showing the tube in an intermediate stage of construction;

Figure 3 is a similar view showing the completed tube;

Figures 4, 5 and 6 are views similar to Figure 3, showing modified forms of the tube;

Figure 7 is a view similar to Figure 1, showing a slightly different form of cup-like member;

Figure 8 is a vertical cross-sectional view of a cup and electrode in place during manufacture of the tube;

Figure 9 is a vertical cross-sectional view of a modified form of cathode, and

Figures 10 and 11 are views similar to Fig-

ure 3, showing further modified forms of the tube.

The invention may be carried into effect according to one form by way of example, see Figures 1, 2, and 3, in the manufacture of a diode valve having a tubular anode and a surrounding hollow cylindrical cathode. A glass cup-like member *a* (see Figure 1) which is to form the envelope, is formed in a mould which causes the wall of the member to be stepped in diameter, forming an internal ledge *b* round the wall, facing the mouth of the member. The portion *c* of the wall of larger diameter adjacent to the ledge has an internal diameter equal to that of the cathode and from this portion the wall is made slightly conical, increasing in diameter from the ledge to the mouth, to facilitate removal from the mould and also to ensure that, when in position, only the rim of the cathode is in contact with the wall. This increase in diameter is shown somewhat exaggerated in all the drawings. The ledge *b* together with the wall portion *c* form an annular re-entrant angle. A hole *d* is blown through the middle of the domed end of the cup-like member.

The anode *e* consists of a small tube of nickel having a support wire *f* of suitable material welded to it. The anode, whilst being mounted, is held in a jig *g* (see Figure 2) having an end which, adjacent to the re-entrant angle, is equal in diameter to that of the cathode and the jig is inserted into the cup-like member so that the wire *f* passes through the hole in its domed end. The jig is inserted until such end abuts against the ledge *b*, and is located against axial movement thereby thus preventing tilting, and for axial alignment the part *c* of the wall adjacent to the ledge. A glass bead *h* is now fused to the end of the member *a* and to the support wire *f*, thus supporting the anode *e* rigidly and sealing the hole *d*. An exhaust tube *i* is also fused into the end near to the bead. The jig is then removed leaving the anode accurately located with respect to the ledge *b* and the adjacent part *c* of the wall.

The cathode *j* (see Figure 3) is in the form of a hollow cylinder having one end closed and a support wire *k* of suitable material welded to the centre of such end. The cathode *j* is inserted into the cup-like member *a* so as to surround the anode *e* until the end of the cathode abuts against the ledge *b* and also makes contact with the part *c* of the wall. With the cathode thus held, the open end of the cup-like member is fused on to the cathode support wire, as shown at *l*, thereby sealing the end and supporting the cathode rigidly.

The tube is then exhausted and activated by any method.

In the description which follows of modifications of the invention, parts which are the same as in Figures 1, 2, and 3, or similar, are given the same or similar reference characters.

In accordance with another embodiment of the invention, see Figure 4, the cathode *j* is carried by a glass dish-shaped member *m* the support wire *k* being passed through a central hole in the domed end to which it is sealed by a glass bead *n*. The cup-like member *a* is constructed as described for Figures 1 and 2 with its anode *e*, and its parts are therefore given the same reference characters. In addition it, and the dish-shaped member *m*, are both provided with integral flanges, formed in the original moulding process or by subsequent flaring, and the flanges of both

members are finally fused together to form the complete envelope. The arrangement is such that, when the said flanges are in contact before fusing, the rim of the open end of the cathode is about 0.5 millimetre from the ledge *b* and during the operation of fusing such flanges the members *a* and *m* are pushed together in order to force the rim against the ledge. When thus closed the cathode *j* is brought into accurate spatial relationship with the anode *e* both axially and transversely as described for Figures 1, 2 and 3.

In a preferred embodiment of the invention, illustrated in Figure 5, the first cup-like member *a* is made as in Figure 2, with its anode *e* but the envelope *a* is somewhat shorter and is formed with an end flange as in Figure 4. For the cathode a second cup-like member *a'* is provided having an internal ledge *b'* formed in its wall in like manner to that described above for the member *a* of Figures 1 and 2. The closed end of the cathode *j* which is the same as shown in Figure 3, is supported by abutment against the ledge *b'* and by contact with the adjacent part *c'* of the wall. In this case the cathode support wire is replaced by a conducting lead *k'*, the cathode being supported entirely by abutment against the two ledges *b* and *b'* and by contact with the adjacent parts *c* and *c'* respectively of the walls when the two cup-like members *a* and *a'* are joined together.

According to a further embodiment, see Figure 6, the cathode *j* is mounted in a second glass cup-like member *o*, but instead of being supported therein by abutment against a ledge and by contact with the adjacent part of the wall, the second cup-like member is provided with internal protuberances, one of which is shown at *p* with which the cathode makes contact as described in the specification of co-pending patent application No. 515,502.

As stated above, the portion of the wall of the cup-like member *a* between the ledge *b* and the mouth is made slightly conical; however, it is desirable that the part *c* adjacent to the ledge *b* should be cylindrical for a length of about 1 millimetre as shown in Figure 7 where the parts have been exaggerated for clarity. Such a short length, whilst not interfering with the removal of the cup-like member from the mould, eliminates lateral displacement should the rim of the cathode not quite abut against the ledge.

In a modification, see Figure 8, the internal diameter of the wall of each cup-like member at the part *c* adjacent to the ledge *b* and which prevents lateral displacement is somewhat larger than the diameter of the cathode *j*. In this case the associated end *q* of the cathode is flared out to equal the full diameter and thus only a thin edge is in contact with the glass. This has the advantage that the area of contact between the cathode and the glass is reduced and the cathode may be heated for degassing purposes without cracking or fusing the glass. This modification may be applied to the construction shown in Figure 5, both ends of the cathode being flared out as shown in Figure 9, where the cathode *j* is formed with flared ends *j'* and *j''*.

The constructions described above lead to the formation of pockets in the space between the electrodes and the envelope, therefore it is desirable to provide holes in appropriate parts of the wall of the cathode to enable the envelope to be evacuated.

The cathode need not be circular in cross-section but may be of any desired shape provided its

rim and the ledge and adjacent part of the wall of the cup-shaped member carrying the anode are of like cross-section.

In all the above embodiments location has been described with reference to the end face of a ledge *b* and the adjacent part *c* of the wall of larger diameter, which together have been described as forming an annular re-entrant angle. In another form however see Figure 10, location may be made with reference to the end face of the ledge *b* together with the adjacent part *c*² of the inner peripheral wall of the internal annular projection forming the ledge which together form an annular projecting angle; the expression annular angle being used hereinafter to cover both re-entrant and projecting angles. As shown also in Figure 10, the reference *j*¹ indicates an extension integral with the mouth of the cathode *j* but of decreased diameter, shaped to engage against the projecting angle formed by the ledge *b* and wall *c*². The arrangement shown at *m* for closing the mouth of the cup-shaped member *a* may of course be replaced by any of the other arrangements described in the specification.

The anode may, if desired, be mounted asymmetrically relative to the cathode by using an appropriate jig. The hollow cylindrical electrode may be the anode instead of the cathode. Furthermore, one or more additional electrodes may be inserted, being held in the same or other jigs similarly adapted for location in the cup-like part *a*. Any such additional electrode, if cylindrical in form, may be supported by an additional ledge and appropriately dimensioned wall adjacent thereto in one of the cup-like members, or in both of them.

The above description has been given with reference to discharge tubes in which at least one electrode is mounted at each end of the tube but the invention is equally applicable to discharge tubes in which the electrodes are mounted at the same end. Thus in the manufacture of a diode valve, for example, as shown in Figure 11, the cup-like member *a*² is provided with two holes at its end and the anode *e* is mounted by means of a jig and sealed with its co-axial conductor wire *f* passing through one of the holes, as described above for Figures 1, 2 and 3. After removal of the jig the cathode *j* is inserted with its rim in contact with the ledge *b*² as in Figure 3, and with the part of the wall *c*³ adjacent to it and its conductor *k*², which is off-set and welded to the inside of the cathode as shown, is passed through the other hole in the cup-like member, to which it is sealed by a glass bead *h*². The mouth of the cup-like member is then closed in any convenient manner, for instance by a flanged dish-shaped member *m*².

The cathode may be of either the cold or hot emissive variety and the discharge tube may be gas-filled or evacuated.

The glass cup-like member is moulded in accurately machined moulds and it may thus be reproduced in quantity accurately. Since the jig and the hollow cylindrical electrode, being of metal, may also be formed with considerable accuracy, it is possible to produce discharge tubes in quantity all of them having substantially identical inter-electrode spatial relationships and hence uniformity of characteristics subject only to slight variation due mainly to other factors, such as the chemical nature of the cathode surface.

What we claim is:

1. An electric discharge tube comprising a

glass envelope having an internal ledge formed by stepping the inner diameter of the wall thereof, at least one electrode mounted at one end of said envelope in predetermined location therein both by reference to said ledge and to the part of the wall adjacent thereto, and another electrode which is prevented from undergoing both axial and tilting displacement by abutment against the said ledge and from undergoing lateral displacement by contact with the said part of the wall adjacent to the said ledge, whereby said electrodes are located in desired spatial relationship to one another.

2. A method of constructing a discharge tube including the formation of at least one internal ledge in a glass cup-like member by stepping the diameter of the wall thereof in such manner that the said ledge faces the mouth of said member, abutting a jig holding at least one electrode against said ledge to prevent both axial and tilting displacement thereof and against the part of the wall of said cup-like member adjacent to said ledge to prevent lateral displacement, mounting the said electrode in the envelope whilst so held by the jig, removing said jig, inserting another electrode into said cup-like member and closing the mouth of the latter member in such a manner as to hold the said other electrode in contact with the said ledge to prevent both axial and tilting displacement thereof and with the part of the wall of the said member adjacent to the said ledge to prevent lateral displacement, whereby the said electrodes are located in desired spatial relationship to one another.

3. An electric discharge tube as claimed in claim 1, in which the portion of the wall of the said cup-like member extending from and facing the ledge formed therein is slightly conical increasing in diameter from said ledge.

4. An electric discharge tube as claimed in claim 1, wherein the part of the wall of larger diameter of said cup-like member adjacent to said ledge is cylindrical for a short length and wherein the wall beyond the said cylindrical part is slightly conical, increasing in diameter from said cylindrical part.

5. A method as claimed in claim 2, wherein the mouth of said cup-like member is closed by fusion of the glass to mount the said other electrode.

6. A method as claimed in claim 2, wherein the mouth of said cup-like member is closed by fusion thereto of a dish-shaped member by which said other electrode is carried.

7. A method as claimed in claim 2, wherein the mouth of said cup-like member is closed by fusion thereto of a second cup-like member provided with at least one internal edge, contact with which is made by said other electrode.

8. A method as claimed in claim 2, wherein the mouth of said cup-like member is closed by a second cup-like member provided with internal protuberances with which said other electrode makes contact.

9. A modification of the method claimed in claim 2, according to which after the insertion of the said other electrode in contact with the said ledge and with the part of the wall of the said cup-like member adjacent thereto, the said electrode is mounted in the said cup-like member whilst so held and the mouth of the said cup-like member is then closed.

10. An electric discharge tube as claimed in claim 1, wherein the said other electrode is provided with a flared-out portion which abuts

against said ledge and an area of the wall adjacent thereto.

11. A diode valve, the anode of which is accurately located both by spaced reference to an internal ledge formed by stepping the diameter of the wall of the envelope and also by spaced reference to the part of the wall adjacent thereto and the cathode of which is prevented from undergoing both axial and tilting displacement by abutment against said ledge and from undergoing lateral displacement by contact with the said part of the wall of the envelope.

12. An electric discharge tube comprising a glass envelope formed internally with an annular angle having continuous peripheral and end faces at least one electrode mounted at one end of the envelope in predetermined location therein by spaced reference to the said peripheral and end faces and at least one other electrode mounted in the said envelope and fully located by abutment with the said peripheral and end faces.

10.
